UNITED STATES PATENT OFFICE

BURTON S. HUGHES, OF BUFFALO, NEW YORK

CENTRIFUGAL COMPRESSOR

Application filed September 22, 1926. Serial No. 136,982.

This invention relates to a centrifugal compressor or vacuum pump which has been designed more particularly for compressing gases or fluids, but which may also be used as a dry vacuum pump for removing air from surface condensers in power plants or as a wet vacuum pump for removing both air and water from surface or jet condensers or from heating systems in buildings.

10 One of the objects of the invention is the provision of a pump of this character which is simple, compact and durable in construction, which is reliable and efficient in operation, and whose parts are so organized and 15 arranged as to reduce the frictional losses to a minimum.

Another object is to provide the pump with novel means for effecting the compression of the gas through the medium of a 20 liquid circulated through the pump.

A still further object of the invention is to so construct the pump that the gas being compressed will be kept in intimate contact with the liquid and thus be maintained 25 close to the temperature of the liquid, whereby the compression will closely approach the isothermal and result in a considerable saving of power over the adiabatic compression of the other types of compressors.

30 In the accompanying drawings:

Figure 1 is a central longitudinal section of a centrifugal compressor or pump embodying my invention. Figure 2 is a transverse section thereof on line 2-2, Fig. 35 1. Figure 3 is an enlarged fragmentary sectional view showing the circulation of liquid and gas through the capillary tubes.

Similar characters of reference indicate corresponding parts throughout the several 40 views.

In the preferred construction of the pump shown in the drawings, the same consists of a cylindrical casing 10 having a suction chamber 11 including an inlet 12 for the admission of gas or other fluid to be compressed and an impeller chamber 13 having an outlet 14 for the discharge of the compressed gas and the liquid used for compressing.

Rotatably mounted in the impeller chamber is a rotor or impeller 15 having a tubu-

lar hub 16 at one end journaled in a suitable bearing 17 located between the suction and impeller chambers, as shown in Fig. 1, and a collar 18 at its opposite end fastened to a driving shaft 19 journaled in a bearing 20 in the adjacent end of the pump-casing and driven by any suitable means. The impeller is hollow, as shown, and its gas-receiving chamber 21 communicates with the suction chamber 11 through the medium of the tubular hub 16. In its peripheral wall, the impeller has a plurality of rows of substantially radial openings or capillary tubes 22 for the discharge of the gas and liquid by centrifugal force into the surrounding portion of the impeller chamber. Completely surrounding the impeller and attached to the same by suitable brackets 23, so as to revolve therewith, is a shroud 24 having inwardly-facing flanges 25 at its opposite ends which are spaced from the contiguous side walls of the impeller and which extend inwardly a suitable distance beyond the periphery of said impeller. Curved blades 26 carried by the impeller and extending into its chamber 21 serve to intercept and direct the liquid used for compressing the gas into the capillary tubes, there being one blade disposed alongside each row of tubes and each blade being curved in a direction to extend over the mouths of its companion tubes. The tips of the blades are suitably spaced from one another to permit the admission of liquid and gas between adjoining blades and thence into the capillary tubes. Arranged in the periphery of the impeller and between the rows of tubes 22 are transverse grooves or recesses 27 which function as discharge ports for the gas, these grooves opening at their ends into the impeller chamber. The bosses or spur-like teeth 28 resulting from these transverse grooves extend part way into the shroud 24 or beyond the side flanges thereof, and the water or other liquid which is contained therein during the operation of the pump forms a seal for the outer ends of the capillary tubes, thus preventing the gas blowing inwardly or back through one or

85 90 95 100

more tubes which might not have received a supply of liquid at their inner ends.

Extending centrally into the chamber 21 of the impeller is a liquid distributing head 29 having slots or perforations 30 for discharging the liquid in comparatively thin radial sheets or in a fine mist into the path of the rotor-blades 26. This head is attached to the inner end of a sectional supply pipe 31 supported on a cover 32 applied to the suction end of the pump-casing. Stuffing boxes 33 and 34 are provided for preventing leakage of the liquid or gas from the impeller chamber into the suction chamber and from the former along the driving shaft 19.

While the impeller 15 may be of any suitable construction, that shown in the drawings is composed of spaced end plates 35 between the outer portions of which is fastened a ring 36 containing the tubes or openings 22. One of the plates has the tubular hub 16 formed integrally therewith while the other plate is provided with the shaft-engaging collar 18.

The operation of this centrifugal compressor is as follows:—

Assume the impeller 15 together with its shroud 24 and blades 26 to be rotating at a high speed by power applied to the driving shaft 19, the gas or other fluid to be compressed entering the chamber 21 of the impeller through the suction inlet 12; and the water or other suitable liquid discharging from the distributor head 29. The water issues from the latter in a plurality of comparatively thin sheets at the required velocity to project it into the path of the moving impeller blades. Each blade intercepts and receives a small quantity of the water discharged from the distributing head, and due to the shape of the blades and the speed of rotation of the impeller, this water travels rapidly by centrifugal force along the inside curved surfaces of the blades and outwardly into the companion capillary tubes 22. The various elements of the compressor are so designed and proportioned that the quantity of water intercepted by a given blade from one of the several sheets issuing from the distributing head is only sufficient to fill a fraction of the length of the corresponding row of tubes. Hence, before a blade intercepts a second supply of water from the next sheet, the first supply has traveled outwardly in the tubes and the space left by such movement is filled with the gas to be compressed. The second supply of water intercepted by the blades follows the gas into their companion tubes, thereby compressing the gas and forcing it outward nearer the outlet ends of the tubes. This action is repeated as the blades continue to intercept the various sheets of water, which may be as numerous as the alternate entrance of water and gas into the tubes will

permit, so as to obtain the maximum volume of gas flow (or displacement) into the compressor. This repeated action, which is illustrated in Fig. 3, results in the several tubes being filled with alternate plugs or columns of gas and water, the gas being compressed in varying degrees and increasing in pressure as it is forced outwardly by centrifugal force acting on such water-plugs. When the compressed gas reaches the outlet ends of the capillary tubes, it is discharged into the water contained in the shroud 24, this water acting as a seal for preventing the gas blowing back through one or more tubes. Because of the rapid rotation of the impeller, the gas is displaced from the shroud and emerges from the water therein into the transverse grooves or ports 27 which are free from water. The gas flows through these ports in either direction and discharges into the surrounding portion of the impeller chamber 13. From the latter, the gas and water pass through the pump outlet 14 to a suitable receiver in which they are thoroughly separated.

It will be understood from the foregoing that as the impeller-carrying tubes 22 are of capillary dimensions for the liquid used, no liquid can pass through them except in the form of a solid plug carrying the gas before it. Furthermore, no tube can get into a state of balance between the resistance due to the pressure on its outer end and the moving force of the contained liquid, for the reason that the liquid is supplied at frequent intervals to the inner end of the tube.

The water used for compressing the gas empties from the tube 22 into the shroud 24, thus establishing and constantly maintaining the liquid seal; the surplus water in the shroud is thrown out into the impeller chamber and thence through its discharge.

Liquids of any density may be employed in the operation of this pump, water, however, serving for most conditions. For high pressure compressions, water solutions of high specific gravity, such as calcium chloride may be used; and for extremely high pressures or high vacua, mercury may be employed.

This centrifugal compressor may be used as a dry vacuum pump for removing air from surface condensers in power plants, or as a wet vacuum pump for removing both air and water from surface or jet condensers. Furthermore, it has low frictional losses due to the impeller revolving in a gas-filled casing and not being immersed in a liquid; also by using a cool liquid, the gas will be kept close to the temperature of the liquid during compression as it is in intimate contact therewith and with the tube-walls which are cooled and wetted by the liquid.

In addition to the uses above mentioned,

this pump can be employed for compressing steam in a recompression evaporator system by using a liquid or solution having a boiling point higher than that of water.

5. I claim as my invention:—

1. A compressor of the character described, comprising a pump-casing having gas and liquid inlets and a discharge, an impeller rotatable in said casing, said impeller having peripheral discharge openings for the passage of the gas and the liquid, and blades carried by the impeller and disposed adjacent the inlet ends of its openings for intercepting and directing successive charges 10 of liquid and gas to said impeller openings.

2. A compressor of the character described, comprising a pump-casing having an inlet for the gas to be compressed and an impeller chamber having a discharge, an impeller rotatable in said chamber and having a gas-receiving chamber communicating with said inlet, the periphery of said impeller having discharge passages for the gas, and blades carried by the impeller and extending 20 into the gas-receiving chamber thereof for directing liquid to said passages for compressing the gas and forcing it outward into the impeller chamber, said blades being curved in a direction to extend over the inlet ends of the impeller-passages to hold a quantity of liquid and the tips of said blades being spaced from one another to admit the liquid and gas between them.

3. A compressor of the character described, comprising a pump-casing including an impeller chamber containing an outlet and a suction chamber containing a gas inlet, a hollow impeller rotatable in said impeller chamber and communicating with said gas inlet and having discharge openings in its periphery, the impeller including blades disposed substantially radially of its inner wall and adjacent the inlet ends of its discharge openings, and means for delivering a compressor-liquid into the path of travel of said blades, said blades intercepting quantities of liquid and the centrifugal force created by the revolving impeller forcing the liquid from the blades into said impeller-openings.

4. A compressor of the character described, comprising a pump-casing having an inlet for the gas to be compressed and an impeller chamber having a discharge, an impeller rotatable in said chamber and having a gas-receiving chamber communicating with said inlet, the periphery of said impeller having a plurality of substantially radial discharge passages for the fluid, a liquid-distributing means for delivering the liquid in thin radial sheets into the gas-receiving chamber of the impeller, and means carried by the impeller for intercepting the sheets of liquid and directing them into said impeller passages.

5. A compressor of the character described, comprising a pump-casing having an inlet for the gas to be compressed and an impeller chamber having a discharge, an impeller rotatable in said chamber and having a gas-receiving chamber communicating with said inlet, the periphery of said impeller having a plurality of passages for conducting the gas into the impeller chamber, blades carried by the impeller and extending into its gas-receiving chamber, and means for delivering sheets of liquid outwardly into the latter, said blades intercepting said sheets and directing the liquid into the impeller-passages to compress and force the gas therethrough.

6. A compressor of the character described, comprising a pump-casing having an inlet for the gas to be compressed and an impeller chamber having a discharge, an impeller rotatable in said chamber and having a gas-receiving chamber communicating with said inlet, the periphery of said impeller having a plurality of passages for conducting the fluid into the impeller chamber, blades carried by the impeller and extending into its gas-receiving chamber, and means for delivering sheets of liquid outwardly into the latter, said blades being curved and extending over the inlet ends of the impeller-passages and adapted to receive and direct the liquid intercepted by them into said passages, whereby the gas is compressed and forced through the same into the surrounding impeller chamber.

7. A compressor of the character described, comprising a pump-casing having an inlet for the gas to be compressed and an impeller chamber having a discharge, an impeller having peripheral discharge passages rotatable in said chamber and communicating with said gas-inlet, means for admitting a liquid into the impeller, means for directing charges of the gas and the liquid to said impeller-passages, and a shroud carried by and encircling the impeller.

8. A compressor of the character described, comprising a pump-casing having an inlet for the gas to be compressed and an impeller chamber having a discharge, an impeller having peripheral discharge passages rotatable in said chamber and communicating with said fluid-inlet, means for admitting a liquid into the impeller, means for directing charges of the fluid and the liquid to said impeller-passages, and a shroud carried by and encircling the impeller and adapted to receive the liquid and gas expelled from said impeller-passages, the outlet ends of the latter extending into the liquid contained in the shroud.

9. A compressor of the character described, comprising a pump-casing having an inlet for the gas to be compressed and an impeller chamber having a discharge, an im-

5 peller having peripheral discharge passages rotatable in said chamber and communicating with said gas-inlet, means for admitting a liquid into the impeller, means for directing charges of the gas and the liquid to said impeller-passages, and a shroud carried by and encircling the impeller and adapted to receive the liquid and gas expelled from said impeller-passages, the periphery of the 10 impeller having gas-escapement ports between adjoining passages, and the outlet ends of the latter extending into the liquid contained in the shroud.

10. A compressor of the character described, comprising a pump-casing having an inlet for the gas to be compressed and an impeller chamber having a discharge, an impeller having peripheral discharge passages rotatable in said chamber and communicating with said gas-inlet, means for admitting a liquid into the impeller, means for directing charges of the gas and the liquid to said impeller-passages, and a shroud carried by and encircling the impeller and having an 20 annular flanges at its opposite edges extending inwardly beyond the periphery of the impeller, said shroud being adapted to receive the liquid and gas expelled from said impeller-passages, the outlet ends of the latter 25 extending into the liquid contained in the shroud and the periphery of the impeller having gas-escapement ports between adjoining passages communicating with the impeller-chamber.

30 11. An impeller for a centrifugal compressor, comprising a chambered-body having discharge passages in its periphery, blades extending into the interior of said body for directing gas and liquid into said 35 passages, and a shroud carried by and surrounding the periphery of said body.

40 12. An impeller for a centrifugal compressor, comprising a chambered-body having substantially radial discharge passages and transverse grooves in its periphery disposed alternately between the outlet ends of 45 said passages, and blades extending into the interior of said body for directing gas and liquid into said passages, said grooves forming 50 escapement ports for the gas.

55 13. An impeller for a centrifugal compressor, comprising a chambered-body having substantially radial discharge passages and transverse grooves in its periphery disposed alternately between the outlet ends of 60 said passages, blades extending into the interior of said body for directing gas and liquid into said passages, said grooves forming escapement ports for the gas, and a 65 shroud carried by and surrounding the periphery of said body and having inwardly-facing flanges at its opposite edges extending part way over the open ends of said grooves.

70 65 14. A compressor of the character de-

scribed, comprising a pump-casing having an inlet and an outlet for both liquid and gas, an impeller rotatable in said casing and including a central chamber communicating with said gas and liquid inlet, said 75 impeller having a plurality of peripheral discharge openings communicating at their inner ends with the chamber of the impeller, blades carried by the impeller and extending into its chamber alongside the discharge 80 openings and over the mouths thereof and shaped to receive and direct the liquid intercepted by them into said discharge openings.
